 corporation of Connecticut

Application May 23, 1940, Serial No. 336,706

17 Claims. (Cl. 235—135)

The present invention relates to registering or counting apparatus and has particular relation to a mechanism including means for registering the total amount or number of units of material dispensed and means for simultaneously registering the total cost of the units dispensed. In the present instance, the mechanism is shown as being adaptable for use with apparatus for dispensing gasoline or other fluids and wherein it is desired to simultaneously register and indicate both the number of units dispensed and the cost thereof.

An object of the present invention is an apparatus of this type wherein the counters are of improved construction and utilize a transfer mechanism whereby the step by step advance of the wheels of higher order is controlled through means driven synchronously with and in direct relation to the wheel of lowest order.

Another object is an apparatus of this type wherein a plurality of counters are utilized and wherein the step by step advance of the wheels of higher order of all of the counters is controlled through means driven synchronously with and in direct relation to the wheel of lowest order.

A further object of the present invention is to provide an improved apparatus of this type wherein the number of parts required is substantially less than the number of parts heretofore required in like apparatus and wherein substantially all of the parts may be metal stampings, thus greatly reducing the manufacturing costs.

A still further object is to provide an improved registering or counting mechanism of the above-indicated type including resetting mechanism and wherein the resetting operations may be easily and quickly effected and the entire mechanism being characterized by its compactness in arrangement, simplicity in operation, and dependability and reliability in service and performance.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a front elevational view of the registering mechanism embodying the invention herein;

Fig. 2 is a plan view of the apparatus shown in Fig. 1;

Fig. 3 is a side elevational view through the center line of Fig. 1;

Fig. 4 is an end view with the front supporting frame removed to show the transfer mechanism and with the parts in position during the resetting operation;

Fig. 5 is an end view showing the means for disconnecting the counters from the drive means therefor;

Fig. 6 is an end view looking from the back of the mechanism and with parts removed to show details of construction;

Fig. 7 is a sectional view through one of the counters to show details of construction;

Fig. 8 is a perspective view of one of the counter wheels;

Fig. 9 is a more or less diagrammatic perspective view showing the transfer mechanism; and

Fig. 10 is a more or less diagrammatic perspective view showing an alternative transfer mechanism.

Referring to the drawings, the mechanism includes a front frame plate 10 and a rear frame plate 12 stamped from any suitable metal and secured together in spaced relation by a plurality of tie rods 14. Supported by the frame plates are a plurality of counters, generally designated as A, B, C, and D; the counters A and B being adapted to indicate the cost of material dispensed and the counters C and D the amount of material dispensed.

Each counter includes, in the embodiment illustrated, three numeral wheels, and referring specifically to counter A, it comprises a numeral wheel 16a of lowest order and a plurality of numeral wheels 18a and 20a of successively higher order. Each of the numeral wheels has indicia on its periphery from "0" to "9"; the lowest order wheel 16a designating units, the wheel 18a tens, and the wheel 20a hundreds. The numeral wheels are mounted for free rotation on a shaft 22a journaled in bushings 24 secured in the frame members 10 and 12 and held against longitudinal movement by collars 26 pinned thereon adjacent the ends of the shaft.

The counters B, C, and D are of like construction, except when otherwise noted, and the parts corresponding to the parts of counter A have been given a similar number with a small letter suffix corresponding to the capital letter designating the counters. As the counters C and D are used to designate the amount of material dispensed, the lowest order wheel is graduated to show tenths, the second order wheel units, and the highest order wheel tens.

To properly arrange the counters, the shafts 22a and 22b are spaced in an upper horizontal plane and the shafts 22c and 22d are spaced in a lower horizontal plane and respectively in vertical alignment with the shafts 22a and 22b, thus positioning a cost and material counter to each side of the mechanism, whereby the cost and the amount of the material dispensed may be simultaneously read through openings provided in the side walls of a usual enclosing casing (not shown).

To drive the counters, there is supported between the frame plates an upper drive shaft 28 located in horizontal alignment with and midway between the cost counter shafts 22a and 22b, and below the shaft 28 a second drive shaft 30 is similarly arranged relative to the material counter shafts 22c and 22d. The drive shaft 28 is connected to a variator (not shown) as, for example, by having pinned thereon a bevel gear 32, which gear meshes with a bevel pinion 34 carried on the upper end of a shaft 36 operatively connected to the variator in any suitable way. In like manner, the drive shaft 30 has pinned thereon a bevel gear 38 having in mesh therewith a bevel pinion 40 carried on the upper end of a shaft 42 operatively connected in any suitable way to the meter (not shown).

Upon rotation of the drive shafts, means are provided for transferring their rotation to the counters aligned therewith, and as the means for accomplishing this and the means for resetting the counters are duplicated in both the cost and amount counters, the description of these parts will, except where otherwise indicated, relate to the cost counter, and like numerals will be employed with like parts of the amount counters, except that the numerals associated with the parts of the amount counters are primed.

To accomplish the transfer of rotation from the drive shaft 28, it has pinned thereon an elongated collar or sleeve 44, and rotatably mounted on the sleeve is a main drive gear 46. The drive gear 46 is located on the sleeve by a positioning plate 48 secured to its back face and having its inner periphery located in a groove 50 cut in the sleeve 44. The means for connecting the drive gear 46 to the drive shaft 28 comprises a clutch, generally designated by the numeral 52, and including a female clutch member 54 secured to the front face of the drive gear 46 and a male clutch member 56 slidably mounted on the sleeve 44. The clutch members are normally maintained in clutching engagement by a spring 58 compressed between the male clutch member 56 and a rearwardly facing radial shoulder 60 on the sleeve 44.

The drive gear 46 is of such size that it meshes directly with a transfer gear 62a (see Fig. 2) directly connected to the lowest order wheel of the counter A and a transfer gear 62b directly connected to the lowest order wheel of the counter B, and thus when the main drive gear 46 is clutched to the drive shaft the lowest order wheels of two oppositely disposed counters will be simultaneously and synchronously rotated in a counting direction; this direction being clockwise when viewed from the front of the mechanism.

To drive the lowest order wheel from its associated transfer gear, the order wheel comprises a cup-shaped member 64a having a discoidal face 66a and a peripheral flange 68a upon which the indicia is printed. The face 66a has a central aperture 70a for mounting same on a hub 72a rotatably carried on the supporting shaft 22a. The hub 72a extends rearwardly from the face

66a for mounting thereon the transfer gear 62a, and the latter is integrally secured to both the lowest order wheel and the hub 72a by a plurality of studs 74a, whereby the entire assembly 5 will continuously rotate as long as the main drive gear 46 is clutched to the main drive shaft.

As is usual, means are provided for advancing the order wheel 18a one step upon the order wheel 18a completing a revolution and for advancing the order wheel 20a one step upon the order wheel 18a completing ten revolutions. In the present instance, this step by step advance is accomplished through transfer mechanism actuated by a means driven by the main drive shaft synchronously with the rotation of the lowest order wheel; in the embodiment illustrated, this means comprising a cam generally designated as 75 and comprising complementary cam members 76 and 78. For convenience in manufacture, the cam members are shown as mounted on the hub 72a of the lowest order wheel 18a and secured by the studs 74a for simultaneous rotation with the transfer gear 62a and numeral wheel 16a.

To utilize the cam 75 for advancing the wheels of higher order, there is associated therewith a transfer lever 80 including a vertically extending long arm 82 having a follower 84 positioned intermediate of its ends and in contact with the cam member 76 and a horizontally extending short arm 86 having a follower 88 at its outer end contacting the cam member 78. The transfer lever 80 is pivoted on a stud 90 extending from the front frame member 10 and of such length that the transfer lever is positioned with the followers 84 and 88 in engagement with their associated cams.

The cam member 76 also has a peripheral incline 92 so located relative to the lowest order wheel 16a that when the numeral "9" of the latter is visible the low point of the incline will contact the follower 84 of the transfer lever, and when the numeral "0" of the lowest order is visible the follower will have reached the top of the incline 92 and pivoted the transfer lever clockwise to the dotted position indicated in Fig. 9. The cam member 78 is constructed in like manner to the cam member 76, but is complementary thereto, and the corresponding incline is advanced sufficiently to enable the follower 88 to always maintain the transfer lever positioned with the follower 84 in engagement with the cam member 78. Obviously a single cam could be used, but the construction shown is advantageous in that the cam members may readily be like metal stamping and merely mounted in complementary positions to obtain the results desired.

To transfer the movement of the transfer lever 80 to the higher order wheels, there is connected thereto means, generally designated by the numeral 94, for advancing the higher order wheels 18a and 20a of the counter A and means, generally designated by the numeral 96, for advancing the higher order wheels 18b and 20b of the counter B. Referring initially to the means 94, it includes a link 98 pivoted at its respective ends to the arm 82 of the transfer lever 80 and the end of a crank arm 100, depending from and pinned to a transfer shaft 102 journaled in the frame plates 10 and 12. Also pinned to the shaft 102 is a second arm 104 of like construction to the arm 100 and so spaced therefrom as to lie in a vertical plane extending centrally between the order wheels 18a and 20a. The lower end of arm 104 has pivoted thereon a laterally extending transfer arm 106 carrying on its free end a

pair of spaced fingers 108 and 110 located between and respectively adjacent the order wheels 18a and 20a. The outer end of finger 108 is bent downwardly to provide a long pawl 112 engaging a ratchet 114a secured to the order wheel 18a whenever the counter is operating in a counting direction, and the finger 110 is bent downwardly to provide a short pawl 116 engageable at predetermined intervals when the counter is operating in a counting direction with a ratchet 118a secured to the order wheel 20a.

The engagement of the short pawl 116 with the ratchet 118a is controlled by the movement of the order wheel 18a by providing the ratchet 114a with nine shallow teeth and one deep tooth, designated by the numeral 120. With this construction, when the long pawl 112 of the transfer arm 106 is positioned in any of the nine shallow teeth of the ratchet 114a, the short pawl 116 will be raised out of contact with the ratchet 118a, the teeth of which are all of like depth to the nine shallow teeth of the ratchet 114a. However, when the deep tooth 120 of the ratchet 114a aligns with the long pawl 112, the pawl will then drop a sufficient distance to position the short pawl 116 behind one of the teeth of the ratchet 118a, this occurring when the numeral "3" of the order wheel 18a is visible, whereupon both wheels will then be simultaneously advanced one step.

As it is essential that the order wheels will not overthrow, means are provided for preventing this from occurring. For this purpose the transfer arm 106 carries on its outer end a transverse stop 122 formed integrally therewith and supported by a pair of spaced fingers 124 and 126 extending outwardly from the base of the pawls 112 and 116.

To cooperate with the stop 122, each wheel of higher order also has secured on its discoidal face a retainer plate 128 having ten laterally extending teeth 130 each having a leading edge 131 and trailing edge 133 with respect to the direction of counting rotation. As seen in Fig. 6, when the transfer arm 106 is at rest with the transfer teeth thereof in engagement with the ratchets, the stop 122 is positioned out of the rotative path of teeth 130. Upon reciprocation of the transfer arm the stop 122 will be carried into the rotative path of the leading edge 131 of a retainer tooth 130, and when the arm reaches the extent of its reciprocating motion the next succeeding retainer tooth 130 will abut the stop 122 and prevent further rotation of the wheel.

Referring now to the means 95 for advancing the higher order wheels 18b and 20b upon rotation of the lowest order wheel of the counter A, the transfer lever 80 has pivoted to the upper end of the long arm 82 a transfer arm 132; the other end of the transfer arm terminating in spaced fingers 134 and 136 positioned between the order wheels 18b and 20b. The outer end of the finger 134 is bent upwardly to provide a long pawl 138 engaging the ratchet 114b of the order wheel 18b, and the outer end of the finger 136 is provided with a short pawl 140 engageable with the teeth of the ratchet 118b of the order wheel 20b. As indicated, this construction is substantially similar to the construction of the arm 106, except that the pawls are turned upwardly, for upon reciprocation of same the ratchets are pushed instead of being pulled. The arm 132 also includes a stop 142 corresponding to the stop 122 of the arm 106, but is positioned intermediate of the ends of the pawl and movable into the ro-

tative path of the retainer teeth when the pawl is reciprocated to advance the order wheels.

It is necessary to also provide means for preventing a reverse rotation of the order wheels as the pawls 106 and 132 are reversely reciprocated following an advance thereof, and this is attained by associating with each wheel of higher order a retainer pawl 144 also adapted to cooperate with the teeth 130 of the order wheel retainer plate 128. To obtain this cooperation, the retainer pawl comprises an arm 146 pivotally mounted at one end on the tie rod 14 and bent upwardly at its other end to provide a shoulder 148. The arm 146 is of such length that it will overlie one of the retainer teeth 130 and position the shoulder 148 as a stop behind the trailing edge 133 of the next retainer tooth 130 in a counting direction. When the order wheel is advanced, the retainer stop underlying the arm 146 will lift same until the shoulder 148 is cleared, whereupon the retainer pawl will again drop into retaining position.

Briefly summarizing the counting operation; upon rotation of the drive shaft 28 the gear 46 will rotate simultaneously therewith and cause synchronous rotation of the lowest order wheels 18a and 18b and of the transfer actuating means—namely, the cam 75. When the numeral "9" of each of these wheels is visible, the incline 92 of the cam member 76 will engage the follower 34 and pivot transfer lever 80 in a clockwise direction to reciprocate the transfer arms 106 and 132 to the dotted lines indicated in Fig. 9, and advance the next highest order wheel one step. Simultaneously, the stops 122 and 142 will move into the path of the order wheel retainer teeth and prevent overthrow thereof. Upon reverse reciprocation of the arms 106 and 132, reverse rotation of the order wheels is prevented by the retainer pawls 144. When the higher order wheels 18a and 18b are so positioned that the numeral "9" is visible, the long transfer pawls will drop into the deep notches of the respective ratchets and engage the short pawls with the next wheel, and upon reciprocation of the transfer arms all the higher order wheels will be advanced one step.

As it is desirable that the higher order wheels will not be advanced with a sudden movement, means are provided for giving the transfer mechanism a harmonious motion. To do this, the incline 92 of the transfer means actuating cam member 76 is so designed as to provide a long gradual rise 93 and a fairly sudden rise 95, and in this manner the pivotal movement of the transfer lever 80 will start at an extremely slow rate and gradually increase as the incline passes over the pawl. In this way it is possible to start the rotation of the higher order wheels prior to the full showing of the numeral "9" of the lowest order wheel. However, the motion of the next higher order wheel will be so slow as not to be noticeable, but will gradually increase in speed so that upon continued rotation it will catch up with the lowest numeral wheel, whereby the two proper numerals will be simultaneously displayed. In this manner, the higher order wheels are not rotated with sudden motion, thus substantially lessening the possibility of overthrow.

Although the ratchets and retainer plates associated with the order wheels have been shown as separate parts, they could be readily stamped from the discoidal faces of the wheels, thus further adding to the simplicity and economy of the mechanism. In like manner, with the exception of the various transfer shafts, practically all of

the parts heretofore described comprise metal stampings. A further advantage of the present structure is that the order wheels could be molded from plastic material, and if this were done the cam 75 could be molded directly on the lowest order wheel and the ratchet teeth and retainer teeth molded directly on the higher order wheels.

Referring to the resetting means, there is provided a centrally located reset shaft 150 journaled in the frame members in like manner to the counter supporting shafts. Upon rotation of the reset shaft it operates means for releasing the transfer pawls from the order wheels, releasing the retainer pawls from the order wheels, clutching the order wheels to their counter shafts, breaking the clutching engagement between the drive shafts and the counters, and thereafter rotating the order wheels and transfer actuating means to zero position. To accomplish these various steps, the reset shaft 150 has pinned thereon a reset cam 152 having a peripheral notch 154, which, when the counters are in zero position, lags behind approximately thirty-seven degrees. Positioned in the notch 154 of the reset cam is a follower 158 carried on the end of a crank arm 158 extending from and pinned to a control shaft 160 journaled in the frame members. The crank arm 158 is normally urged towards rotation in a clockwise direction by a spring 162 having one end connected to the arm and the other to the frame member, and this rotation also tends to rotate the reset shaft in a counterclockwise direction.

To limit this rotation of the arm 158 and the reset shaft, the control shaft 160 also carries a non-back-up lever 164 which engages the periphery of a non-back-up cam 166 carried on the hub of the reset cam 152. The non-back-up cam includes a reverse facing shoulder 168 engaging the end of the non-back-up lever 164 when the reset cam is at zero position, and a second reverse facing shoulder 170 trailing the shoulder 168 and engageable with the non-back-up lever 164 after the reset shaft has been rotated to lift follower 158 out of the notch 154 and onto the periphery of the reset cam and thereafter necessitating a full rotation in a reset direction.

Upon the lifting of follower 158 out of the notch, the arm 158 and control shaft 160 will both be rotated in a counterclockwise direction. When this occurs, the shaft 160 will also rotate a pair of crank arms 172 pinned thereon at one end and pivotally and slidably connected at their opposite ends to spaced actuating slides 174 positioned in vertical alignment and in a plane midway between the two higher order wheels of each counter. For mounting the slides, there is cut therein slots 176, 178, and 180 through which the drive shafts 28 and 30 and the reset shaft 150 extend; the top and bottom of the slots acting as stops to limit the vertical movement thereof. Upon the slides being raised vertically, they function to release the transfer pawls and retainer pawls from their ratchets and simultaneously clutch the order wheels to the counter shafts, positioning the parts as indicated in Fig. 4. To release the pawls, the slides have struck out laterally extending tongues 182 engageable beneath the transfer arms 106 and 132 for lifting same out of contact with their associated ratchets. As the transfer arms are raised, they in turn engage depending tongues 184 provided on each of the retaining pawls 144, thus lifting

same from behind the retainer stops 130, whereby the order wheels will be free to rotate on their counter shafts.

To clutch the order wheels to their respective counter shafts, the slides also actuate four levers 186, one associated with each counter. As seen in Fig. 4, one end of each lever 186 is slidably and pivotally mounted on a slide and the other end 188 is pivotally mounted on the counter shaft intermediate of the two higher order wheels of the counter with which it is associated. As the slide is raised, the lever 186 will be rotated to slightly rotate a pair of oppositely disposed cams 190 provided on the pivoted end 183 of the lever 186; these cams merely being detents provided in the lever when the same is stamped out.

To cooperate with the cams 190, there is also arranged between each pair of higher order wheels a vertically arranged spacer 192 provided with apertures alignable with the counter shafts to permit its mounting thereon and extending above and below the shafts and between the pawl arm transfer fingers to function as guides therefor. The spacer 192 includes a pair of cams 194 complementary to the cams 190 and so positioned relative thereto that upon rotation of the lever 186 the cams 190 will ride onto the cams 194. When this occurs, the spacer 192 and the inner end 188 of the lever 186 will spread apart and each will engage against a friction spring 196 keyed to the counter supporting shaft so as to rotate therewith but be slidable thereon. As seen in Fig. 8, the spring 196 includes a central body portion 197 and a plurality of fingers 198 bent out of the plane of the body portion to abut against the discoidal face of the order wheel with which it is associated. When pressure is applied to the body portions, the fingers will frictionally engage against the wheel and clutch it to the counter shaft for rotation therewith, although permitting slippage if the frictional force is overcome. Simultaneously, the intermediate order wheel will also be moved longitudinally of the counter shaft, and the forward end 45 of its hub will compress a friction spring 198 associated with the drive gear of the lowest order wheel (see Fig. 7) to clutch it to the counter shaft, whereby upon rotation of the counter shaft all the wheels may reset to zero.

To simultaneously disconnect the drive gears 46 and 46' from the drive shafts, there is slidably mounted on the reset shaft 150 a yoke 200 having its top and bottom ends positioned in a collar 202 provided on each of the male members of the clutches 52. To slide the yoke 200 longitudinally of the reset shaft and thus break the main drive clutches, there is associated therewith one end 204 of a toggle link 206, which end is provided with cams 208 normally aligned with and positioned in a vertical groove 210 in the yoke 200. The end 204 of the toggle link 206 is maintained in proper position by a collar 212 pinned to the reset shaft 150 rearwardly of the link.

To actuate the link 206, it is connected through 65 a second toggle link 214 to the control shaft 160, and upon rotation of the latter the toggle will move from its normal position indicated by full lines in Fig. 5 to the broken line position to rotate the cams 208 out of the yoke groove 210 onto the face of the yoke, sliding the latter longitudinally of the reset shaft and breaking the clutches between the drive shafts and the drive gears.

All of the foregoing occurs as the reset cam 75 75 is rotated from the position indicated in Fig.

1 to the position indicated in Fig. 4, and thereafter the resetting rotation of the counter wheel occurs. To accomplish this resetting, the shaft 150 extends forwardly of the frame plate 19 and has mounted on its outer end a lever 216 engageable with a stud 218 mounted on the face of a main reset gear 220. The main reset gear is rotatably mounted on a hub 222 pinned to the lever 216 and is normally held stationary by friction means including a plate 224 having a depending finger 226 pinned to the frame plate 19. Rearwardly of the plate 224 is a friction spring 228 of like construction to the friction spring 198 and normally held under compression by a securing washer 230 seated in a groove in the hub 222. There may also be positioned between the spring 228 and plate 224 a friction washer 232 and a like friction washer positioned between the plate 224 and the rear face of the main reset gear 220.

The reset gear 220 simultaneously meshes with a secondary reset gear 234 pinned on the forward end of each of the counter supporting shafts, and thus upon rotation of the main reset gear all of the counter shafts will be rotated in a counterclockwise direction, and as the order wheels have been previously clutched to the counter shafts, they will be simultaneously rotated towards zero position and the transfer actuating means rotated simultaneously with the lowest order wheel. As this rotation is in a direction opposite to the counting direction and independent of any movement of the drive means, backlash is eliminated.

To assure accurate zero setting, each higher order wheel retainer plate 128 includes one stop 236 having a trailing edge 187' at a greater radial distance from the center of the wheel than those of the remaining stops 130. This stop is so located that when zero becomes visible the stop will engage the stop shoulder 148 of the retaining pawls 144; these pawls having only been raised sufficiently to permit the other retainer stops to clear same upon the resetting operation. When so held, the friction clutch will slip and the counter shaft rotate independently of the order wheel.

To stop the lowest order wheels at zero, the main drive gears 46 and 46' are provided with a stud 238 which engages the vertical edge 239 of a stop 240 pivotally mounted on the transfer pawl oscillating shaft 102. As seen in Fig. 3, the stop 240 may comprise a U-shaped stamping which overlies the periphery of the main drive gear and has at its pivoted end a side facing shoulder 242 which will abut against the tie rod 14 and limit the pivoting of the stop in a counterclockwise direction, and a downwardly facing shoulder 244 which will limit the pivoting in a clockwise direction. Obviously as the main drive gear moves in a counting direction the stud 238 will ride beneath the stop 240 and simply lift it out of its path of movement, and the stop will drop by gravity when the stud has cleared same.

To assure that all of the wheels will be rotated to zero position, the gear ratio between the main reset gear 220 and the secondary gears 234 is such that the latter will be rotated approximately one and one-quarter times for each revolution of the main reset gear. Thus should any slippage occur between the order wheels and the counter shafts, the extra extent of movement will compensate for same.

Upon completing a revolution of the reset shaft, the follower 156 of the arm 158 will again be

drawn by the tension of spring 162 into the notch 154 to reverse the rotation of the reset shaft through the medium of the spring 162 until the non-back-up lever 164 engages behind the non-back-up cam shoulder 168. When this occurs, the control shaft 160 will be rotated in a clockwise direction and, through its associated mechanism, will move the actuating slides downwardly and reset the various parts for counting operation.

In the embodiment illustrated in Fig. 10, there is shown an alternative means for advancing the higher order wheels of each counter. In this embodiment, the means for advancing the ratchets 114b and 118b of the numeral wheels 18b and 20b of the counter B is similar to that shown in Fig. 9, and the parts have been similarly numbered. However, to advance the ratchets 114b and 118b of the numeral wheels 18a and 20a, the pawl carrying arm 106, instead of being driven through interconnecting linkage to the lever 80, is directly driven by means rotated synchronously with the transfer gear 62b and the lowest numeral wheel 16b of the counter B. These means include a transfer lever and cam lever of like construction to those associated with the lowest numeral wheel of the counter A and have been given like numerals.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In combination, a pair of counters each having a plurality of numeral wheels of successively higher order, means for synchronously rotating the wheel of lowest order of each counter, oscillatable transfer means for the wheels of higher order, and means rotated in synchronism with the wheels of lowest order for operating said oscillatable transfer means to effect a transfer movement of the wheels of higher order.

2. In combination, a pair of counters each having a plurality of numeral wheels of successively higher order, means for synchronously rotating the wheel of lowest order of each counter, and transfer means for effecting a transfer of the wheels of higher order and including a cam rotated in synchronism with the wheels of lowest order and a pawl and ratchet associated with each wheel of higher order and operatively connected to the cam.

3. In combination, a pair of counters each having a plurality of numeral wheels of successively higher order, means for synchronously rotating the numeral wheels of lowest order, transfer pawls for the wheels of higher order, means for operating said transfer pawls for effecting a transfer movement of the wheels of higher order and including an actuating member rotated synchronously with said wheels of lowest order, and operative connections between said actuating member and said transfer pawls.

4. In combination, a pair of counters each having a plurality of rotatable numeral wheels, a

rotatable drive shaft, and means for advancing said numeral wheels after a predetermined rotation of the drive shaft and including an actuating member rotated synchronously with the drive shaft, and oscillatable means operatively connected to said numeral wheels and periodically operated by said actuating member to rotate said numeral wheels.

5. In combination, a pair of counters each having a plurality of numeral wheels of successively higher order, means for synchronously rotating the wheels of lowest order of each counter, common transfer means for advancing all of the wheels of higher order of both of said counters, and means associated and rotated synchronously with the lowest order wheel of one of said counters for actuating said transfer means.

6. In combination, a pair of counters each having a plurality of numeral wheels of successively higher order, means for synchronously driving the lower order wheels of each of said counters, and means rotated synchronously with the driven wheel of one counter for advancing the higher order wheel of the other counter.

7. In combination, a pair of counters each having a plurality of numeral wheels of successively higher order, means for synchronously rotating the wheels of lowest order, transfer means movable in reverse directions and operable when moved in one direction for advancing the wheels of higher order in a counting direction, and means rotated synchronously with the rotation of the wheel of lowest order for operating said transfer means in reverse directions.

8. In a counter, a numeral wheel of lowest order, second and third numeral wheels of successively higher order, means for rotating said lowest order wheel, a transfer pawl engageable with said second wheel, a second transfer pawl engageable with said third wheel, means on the second wheel for controlling the engagement of the second transfer pawl with the third wheel, and means rotated synchronously with the lowest order wheel for actuating both of said transfer pawls.

9. In a counter, a numeral wheel of lowest order, a second numeral wheel of higher order, a reciprocating pawl associated with said second wheel for advancing same after a predetermined rotation of the first wheel, and rotatable means operated synchronously with the rotation of the lowest order wheel for reciprocating said pawl.

10. In combination, a pair of counters each having a plurality of numeral wheels of successively higher order, means for synchronously driving the lower order wheels of each counter, transfer means for the higher order wheels including a ratchet associated with each wheel and a pawl for operating said ratchet, and means for operating said pawls comprising a member rotated synchronously with the driven wheel of one counter and operatively connected to each of said pawls.

11. In combination, a pair of counters each having a plurality of numeral wheels of successively higher order, means for synchronously driving the lower order wheel of each of said counters, and means for operating the higher order wheels of each of said counters including a ratchet associated with each wheel and a pawl

for operating said ratchet, and means for operating said pawls including a member synchronously driven with the driven wheel of one counter and operatively connected to the pawls of the other counter.

12. In a counter having a pair of order wheels of successively higher order, drive means for rotating the wheel of lowest order, pawl and ratchet means for advancing the wheel of higher order on predetermined rotation of the wheel of lower order, and an operative connection between said pawl and said drive means and including a first member rotated synchronously with the lowest order wheel and a second member operated by the first member for converting the rotating movement of said first member into oscillating movement to oscillate said pawl.

13. In combination, a pair of counters each having a plurality of numeral wheels of successively higher order, drive means for simultaneously rotating the wheel of lowest order of each counter, transfer means for the higher order wheels including a ratchet associated with each wheel and a pawl for operating said ratchet, and means for operating said pawls comprising a cam simultaneously rotated with the wheels of lowest order.

14. In a counter, a plurality of numeral wheels of successively higher order, drive means for the wheels of lowest order, transfer means for the higher order wheel comprising a ratchet associated with the wheel and a pawl for operating the ratchet, means for operating said pawl and comprising a cam operatively connected to said drive means for synchronous rotation with the wheel of lowest order, and operative connections between said cam and said transfer pawl.

15. In a counter, a plurality of numeral wheels of successively higher order, means for driving the lowest order wheel, means for advancing the highest order wheels after a predetermined rotation of the lowest order wheel, said means comprising a pawl associated with each wheel, a transfer lever to which said pawls are commonly connected, and a member rotated synchronously with the lowest order wheel for actuating said transfer lever.

16. In a counter, a plurality of numeral wheels of successively higher order, drive means, means for actuating said order wheels and comprising a pawl associated with each wheel, a transfer lever to which said pawls are commonly connected, and a member having an operative connection to said drive means for synchronous rotation therewith for oscillating said transfer lever.

17. In combination, a pair of counters each having a plurality of numeral wheels of successively higher order, means for synchronously rotating the wheel of lowest order of each counter, and means for effecting a transfer movement of the wheels of higher order following a predetermined rotation of the wheel of lower order and comprising a ratchet associated with each wheel and a pawl for operating said ratchet, and means for operating the pawls comprising a transfer lever to which said pawls are commonly connected and a member operated synchronously with said lowest order wheel for actuating said transfer lever.
